UNITED STATES PATENT OFFICE

ALFRED W. BRUCE, OF NEW YORK, N. Y.

LOCOMOTIVE BOILER

Application filed February 3, 1928. Serial No. 251,508.

This invention relates to means for supporting the crown sheets, increasing the area of heating surface, and promoting the circulation of water in the fireboxes of locomotive boilers of the general class or type in which water walls are applied within said fireboxes. An early instance of such a construction is set forth in the patent of J. E. McConnell, No. 17,436, dated June 2, 1857.

10 The object of the present invention is to provide an appliance, of simple and inexpensive construction and ready applicability in locomotive boilers of present standard constructions, in the operation of which the crown sheet will be firmly supported, increase of water heating surface be made, and circulation of water in the firebox be promoted.

The improvement claimed is hereinafter fully set forth.

20 In the accompanying drawings: Figure 1 is a fragmental vertical longitudinal section, on the line I—I of Fig. 2, through the rear portion of a locomotive boiler, illustrating an embodiment of the invention; Fig. 2 a fragmental half plan view, partly broken away, of the same; Fig. 3 a vertical transverse section, the left hand half being taken on the line III—III of Fig. 1, and the right hand half on the line, III'—III' of the same figure; Figs. 4 to 9 inclusive are enlarged fragmental views; Fig. 4 a section taken on the line IV—IV of Fig. 5; Fig. 5 a half front view of parts shown in Fig. 4 and a half sectional view taken on the line V—V of Fig. 4; Fig. 6 a plan view of parts shown in Fig. 4; Fig. 7 a modified form of the parts shown in Fig. 4 taken on the line VII—VII of Fig. 8; Fig. 8 a front view of the parts shown in Fig. 7; and Fig. 9 a plan view of parts shown in Fig. 7.

40 In the practice of the invention, referring descriptively to the specific embodiment thereof which is herein exemplified as applied in a locomotive boiler of the standard combustion chamber class, having a firebox, indicated, as an entirety, by A; a waist or barrel, indicated by B, and a combustion chamber, indicated by C, two or more crown sheet supporting and water circulating members, 45 1, 1, are located in the forward portion of the

firebox, A, and the adjoining portion of the combustion chamber. Said members are vertical water walls, of substantially triangular outline, the upper and wider ends of which are open to the space within the boiler above 55 the crown sheet, 2. The upper ends of the plates which form the water walls, are secured, by rivets, to upwardly turned flanges 2a, on the crown sheet and adjoining sheet of the combustion chamber, one or more rows of the radial staybolts, 2b, by which said sheets are connected to the shell sheets of the boiler, being omitted, to afford space for the insertion of the water walls, as clearly indicated in Fig. 2.

A pipe 4 leads from the waist of the boiler to a header 4a which communicates with the lower ends of each of the members 1. A pair of header supports 5 are secured at their front ends to the mud ring front portion 6 and at their rear ends to a transverse bar 7 secured at its ends each to a side of the mud ring. The header 4a is provided with the bottom plate 4b which may be removed for the purpose of cleaning the header. Arch tubes 8 75 are provided, the rear ends of which are secured in the upper rear portion of the fire box A and the front ends of which are secured in the rear portion of the header 4a. A second set of arch tubes 9 are likewise supported at 80 their rear ends in the upper part of the rear end of the fire box A, the front portions of which pass between the water legs with their ends connected in the rear of the throat 10 of a portion 13 of the waist B which extends 85 about the combustion chamber C. An arch 11 of fire brick is supported upon the arch tubes which extends through the front portion of the fire box A and the rear portion of the combustion chamber C. 90

In the construction of Figs. 7 to 9 inclusive, is shown a modified structure wherein, instead of the supports 5, lateral supporting plates 12 are employed, which, in the present instance, are formed integral with the header 95 12a and have their outer ends 12b secured to the sides of the mud ring 12c.

The invention claimed and desired to be secured by Letters Patent, is:

1. In a steam boiler of the locomotive type,

the combination of a crown sheet; a plurality of spaced substantially vertical water walls, having open upper ends secured to upwardly projecting flanges on said crown sheet; a transversely extending header, rigidly connected to, and communicating with the lower ends of the water walls; arch tubes having their lower ends secured in said header; and a pipe leading from the waist of the boiler to the header.

2. In a steam boiler of the locomotive type, the combination of a crown sheet; a plurality of spaced substantially vertical water walls, having open upper ends secured to upwardly projecting flanges on said crown sheet; a transversely extending header, rigidly connected to, and communicating with the lower ends of the water walls; arch tubes having their lower ends secured in said header; a pipe leading from the waist of the boiler to the header; and a cradle member rigidly secured to the header and to the bottom of the firebox.

3. In a stem boiler of the locomotive type, the combination of a crown sheet; a waist; an inner throat sheet; a plurality of spaced substantially vertical water walls having open upper ends secured to said crown sheet; a header disposed rearwardly of the inner throat sheet, rigidly connected to, and communicating with, the lower ends of the water walls; and a passageway leading from the waist to the header.

4. In a steam boiler of the locomotive type, the combination of a crown sheet; a mud ring; a waist; an inner throat sheet; a plurality of spaced substantially vertical water walls, having open upper ends secured to said crown sheet; a header disposed rearwardly of the inner throat sheet, rigidly connected to, and communicating with, the lower ends of the water walls; and a passageway leading from the waist, below the mud ring to the header.

45 5. In a steam boiler of the locomotive type, the combination of a crown sheet; a waist; an inner throat sheet; a plurality of spaced substantially vertical water walls, having open upper ends secured to said crown sheet; a header disposed rearwardly of the inner throat sheet, rigidly connected to, and communicating with, the lower ends of the water walls; a passageway leading from the waist to the header; and arch tubes communicating with the header.

60 6. In a steam boiler of the locomotive type, the combination of a crown sheet; a mud ring; a waist; an inner throat sheet; a plurality of spaced substantially vertical water walls, having open upper ends secured to said crown sheet; a header disposed rearwardly of the inner throat sheet, rigidly connected to, and communicating with, the lower ends of the water walls; a passageway leading from the waist, below the mud ring, to the header;

and arch tubes communicating with the header.

7. In a steam boiler of the locomotive type, the combination of a fire box; a combustion chamber; a crown sheet; a rear flue sheet at the front end of the combustion chamber; a waist extending each side of the sheet the part to the rear of the sheet enclosing the combustion chamber; a throat at the rear end of the waist; a plurality of spaced substantially vertical water walls disposed partly in the fire box and partly in the combustion chamber and having their upper ends opening into the boiler above the crown sheet; a header disposed rearwardly of said throat and below said waist, and rigidly connected to, and communicating with, the lower ends of the water walls, the bottom portion of said water walls being in communication with the bottom part of the waist; a pipe connecting the header with the waist; and arch tubes directly connected at one end to the throat.

8. In a steam boiler of the locomotive type, the combination of a fire box; a combustion chamber; a crown sheet; a rear flue sheet at the front end of the combustion chamber; a waist extending each side of the sheet the part to the rear of the sheet enclosing the combustion chamber; a throat at the rear end of the waist; a plurality of spaced substantially vertical water walls disposed partly in the fire box and partly in the combustion chamber and having their upper ends opening into the boiler above the crown sheet; a header disposed rearwardly of said throat and below said waist, and rigidly connected to, and communicating with, the lower ends of the water walls, the bottom portion of said header being in communication with the bottom part of the waist; arch tubes directly connected at one end to the throat; and other arch tubes directly connected with the header.
